UNITED STATES PATENT OFFICE.

WILLIAM H. SARGENT, OF ST. LOUIS, MISSOURI, ASSIGNOR TO WAYNE MANUFACTURING COMPANY, OF ST. LOUIS, MISSOURI, A CORPORATION OF MISSOURI.

GEARING.

1,320,577.

Specification of Letters Patent.

Patented Nov. 4, 1919.

Application filed July 27, 1917. Serial No. 183,087.

To all whom it may concern:

Be it known that I, WILLIAM H. SARGENT, a citizen of the United States, residing at the city of St. Louis and State of Missouri, 5 have invented a new and useful Gearing, of which the following is a specification.

This invention relates to gearings.

In the embodiment illustrated the invention has special reference to gearings for 10 operating washing machines, though it will be understood that the use of the gearing is not confined to washing machines but may well be employed in any other embodiment in which the results or functions accomplished by the invention are desired.

An object of the invention is to provide 15 a gearing comprising a drive shaft, a shaft to be driven mounted in a support which is movable relative to the drive shaft, and 20 gearing for driving the driven shaft from the drive shaft in one position of said support, in combination with mechanism for preventing operation of the driven shaft by the drive shaft when said support is in another position.

Another object of the invention is to provide 25 a novel operating gearing for washing machines comprising a drive shaft, a driven shaft mounted in the movable lid or cover 30 of the washing machine, a gearing for driving the driven shaft from the drive shaft when the lid or cover is in closed position, and means for rendering the gearing inoperative when the lid or cover is moved to 35 open position so that the shaft supported by the lid or cover will not be operated when the lid or cover is out of closed position.

With the foregoing and other objects in 40 view, I have produced an efficient embodiment of the invention and have illustrated the same in the accompanying drawings, in which—

Figure 1 is a plan view of my improved 45 gearing applied to a washing machine.

Fig. 2 is a side elevation.

Fig. 3 is a plan view of the gearing showing the clutch device released.

The present invention is shown in combination with a part of the gearing mechanism disclosed in my prior application Serial No. 52,615, filed September 25, 1915.

As illustrated in the drawings the tub 1 constitutes a support for the driving mech-

anism and the lid or cover 2 constitutes a 55 support for the driven mechanism.

A frame including the two arms 3 is secured to the lid 2 by bolts 4. The extremities of the arms 3 are provided with bearings 5 which are pivoted upon the drive 60 shaft 6, the latter being journaled in bearings carried by the tub, one of which is shown at 6^a. The frame of which the arms 3 are a part constitutes a hinge for the lid or cover, the shaft 6 being the pivot of the 65 hinge. A beveled pinion 7 is loosely mounted on the shaft 6 and meshes with a bevel pinion 8 supported on a shaft 9. The shaft 9 is at right angles to the shaft 6 and is journaled in a bearing 10 formed in the 70 frame of which the arms 3 are a part. Said frame is also provided with a rising portion 11 at the upper part of which a bearing 12 is formed. A shaft 13 is journaled in the bearing 12 and in a bearing 14 which is 75 formed in a frame 15 secured to the lid or cover 2 of the washing machine. A pinion 16 attached to the shaft 13 meshes with a peripheral series of teeth 17 formed in connection with the pinion 8.

80 A vertical shaft 18 is journaled in bearings in the frame 15 for axial and rocking movements. Axial movements are imparted to the shaft 18 by the shaft 13 through a crank connection 19 which moves the shaft 85 18 axially in opposite directions when the shaft 13 is in rotation. Rocking movements are imparted to the shaft 18 by reciprocation of a rack 20 which meshes with a pinion 21 on the shaft 18. One end of said 90 rack 20 is connected to a crank pin 22 extending from a pinion 23 revolubly supported upon an axial member 24 above the bearing 12. The pinion 23 is a beveled pinion and is in mesh with a pinion 25 attached to the shaft 13 so that the pinion 23 95 will be constantly rotated and the shaft 18 will be given an alternating rotary movement by the constant rotation of the shaft 13 in one direction.

100 No claim is made herein to the specific construction of the rack 20 and pinion 21, nor are said parts illustrated in complete detail in the accompanying drawing for the reason that they are clearly and fully shown 105 and constitute a part of the subject-matter of my above-named application Serial No. 52,615.

As previously stated, the pinion 7 is loose upon the shaft 6. For driving the pinion 7 by the shaft 6 a clutch device is provided which in one position locks the pinion to the shaft and in another position releases the pinion to enable the shaft to rotate without driving the pinion. This clutch device may assume any convenient form and, as illustrated comprises a sliding clutch member 26 feathered or splined upon the shaft 6, and adapted to engage a coöperating clutch member 27 rigid with the pinion 7. The clutch member 26 is actuated to clutch engagement with the member 27 by a spring 28 encircling the shaft 6 between the clutch member 26 and the adjacent bearing 5.

As a result of this construction the pinion 7 is normally locked to the shaft 6, and the shaft 18 will be constantly operated when the shaft 6 is in rotation. However, it is desirable in washing machines to provide means for stopping or preventing operation of the shaft 18 when the lid or cover is raised to open position. Heretofore machines have been constructed with manually operative means for throwing the operating mechanism out of gear at the option of the operator of the machine. The manipulation of the manual means requires special thought or consideration and on some occasions has been overlooked, as a consequence of which the shaft 18 continues to operate when the lid or cover of the washing machine is opened. The operating mechanism or agitator of the washing machine is thus liable to become caught or engaged in the clothing of the operator of the machine and cause more or less serious injury. Therefore, it is highly important that provision be made for automatically throwing the operating mechanism out of gear as an incident to opening of the lid or cover of the washing machine. This automatic mechanism constitutes an essential part of my present invention, and I will now proceed to a description thereof.

A clutch operating rod 29 is mounted for axial and rocking movements in bearings 30 extending from the bearing 6^a in which the drive shaft is journaled. The inner end of the rod 29 supports a collar 31 having two arms 32 extending into a circumferential groove 33 in the clutch member 26. Thus when the rod 29 is moved axially in an outward direction the clutch member 26 is disengaged from the clutch member 27 and the spring 28 is placed under compression. A cam 34 is formed on one of the bearings 30 and a matching cam 35 is connected to the rod 29. An arm 36, in connection with the rod 29, constitutes means for operating the cam 35 as required to move the rod 29 in order to disengage the clutch member 26 from the clutch member 27. The arm 36 bears against the lid or

cover 2, and when the lid or cover is closed the two cam parts occupy the relative positions illustrated in Fig. 1, in which the two clutch members 26 and 27 are engaged. However, when the lid or cover is raised to open position the arm 36 is actuated and turns the cam 35 against the cam 34, thus moving the rod 29 outwardly and disengaging the clutch member 26 from the clutch member 27, as illustrated in Fig. 3. The cam members 34 and 35, however, do not become locked in the position shown in Fig. 3, but permit the spring 28 to actuate the clutch member 26 into clutching engagement with the member 27 automatically as an incident to closing of the lid or cover 2. Thus no attention is required from the operator to throw the operating mechanism into or out of gear when the lid or cover of the washing machine is opened and closed.

It will be understood that the operating mechanism for the shaft 18 may be widely varied from that disclosed without in the least departing from that part of the invention which comprises the gearing control mechanism. It is equally apparent that the gearing control mechanism, which is operated by the movement of the lid or cover of the washing machine to throw the operating mechanism out of gear and which operates automatically to reengage the operating mechanism is in no sense dependent upon the specific form of gearing by which the shaft 18 is driven by the shaft 6. Therefore, in illustrating and describing my invention, I do not in any sense confine myself to the specific arrangement and combination of parts shown, but what I claim and desire to secure by Letters Patent, is:—

1. A gearing, comprising a stationary support, a drive shaft journaled in said support, a pinion loose on said drive shaft, an additional pinion meshing with the pinion on the drive shaft, a device for locking the first-named pinion to and unlocking the same from said drive shaft, an actuator on the drive shaft for moving said device to position to lock said first-named pinion to the drive shaft, a movable support hinged to said drive shaft, mechanism carried by the movable support driven by said additional pinion, and means operated by said movable support for moving said device to position to unlock said first-named pinion from said drive shaft as an incident to movement of said movable support from one position to another, whereby said additional pinion and the mechanism carried by said movable support will be permitted to stop while said drive shaft continues to operate.

2. A gearing, comprising a stationary support, a drive shaft journaled in said support, a movable support, hinge members connecting said movable support with said drive

shaft, a driven shaft mounted in said movable support, gearing for driving said driven shaft from said drive shaft, a device for rendering said gearing inoperative for driving said driven shaft, cams for moving said device to render said gearing inoperative to drive said driven shaft from said drive shaft, and a lever operated by said movable support for causing said cams to move said device to render said gearing inoperative for driving said driven shaft from said drive shaft and thereby permit said driven shaft to stop, as an incident to movement of said movable support from one position to another, while said drive shaft continues in operation.

3. A gearing, comprising a stationary support, a drive shaft carried thereby, a movable support hinged to said drive shaft, a driven shaft carried by said movable support, gearing for driving said driven shaft from said drive shaft, a clutch device for locking a part of said gearing with said drive shaft, and means operated by said movable support for releasing said clutch device when said movable support is moved from one position to another.

4. A gearing, comprising a stationary support, a drive shaft carried by said support, a movable support hinged to said drive shaft, a drive shaft mounted in said movable support, gearing for driving said driven shaft from said drive shaft, a clutch device for locking a part of said gearing to said drive shaft, means holding said clutch device in clutching engagement when said movable support is in one position, and means operated by said movable support for moving said clutch device to position to release said gearing when said movable support is moved from one position to another.

5. Gearing of the character described, comprising a stationary support, a drive shaft carried by said support, a pinion loose upon said drive shaft, a movable support, a driven shaft mounted in said movable support, gearing for operating said driven shaft from said pinion, a clutch member on said drive shaft for locking said pinion thereto, means holding said clutch member in locking position when said movable support is in one position, and means for moving said clutch member to position to release said pinions when said movable support is moved from one position to another.

6. Gearing of the character described, comprising a drive shaft, a pinion loosely mounted on said drive shaft, a clutch member movable to and from position to lock said pinion in connection with said drive shaft, a spring actuating said clutch member to position to lock said pinion in connection with said drive shaft, an actuator for moving said clutch member to position to release said pinion, a movable support, gearing for operating said mecha-

shaft carried by said movable support, gearing arranged to be operated by said pinion to operate said shaft when said pinion is locked to said drive shaft by said clutch member, and means for operating said actuator to release said clutch member when said movable support is moved from one position to another.

7. Gearing of the character described, comprising a drive shaft, a pinion loosely mounted on said drive shaft, a support hinged to said drive shaft, a driven shaft carried by said support, gearing controlled by said pinion for operating said driven shaft, a clutch device for locking said pinion in connection with said drive shaft to cause said pinion to operate said gearing and thereby said driven shaft in one position of said support, and an actuator operated by said support to release said clutch member from said pinion by movement of said support from one position to another.

8. Gearing of the character described, comprising a stationary support, a drive shaft carried by said stationary support, a movable support, hinges connecting said movable support with said drive shaft and enabling said movable support to be moved relative to said drive shaft, mechanism carried by said movable support, means for operating said mechanism from said drive shaft when said movable support is in one position, and a device actuated by said movable support for rendering said operating means inoperative as an incident to movement of said movable support from one position to another, and while said drive shaft continues in operation.

9. Gearing of the character described, comprising a stationary support, a drive shaft carried by said stationary support, a pinion loose upon said drive shaft, a clutch for locking said pinion to said drive shaft, an actuator for releasing said clutch from said pinion, a movable support, mechanism carried by said movable support, gearing for operating said mechanism from said pinion when said pinion is locked to said drive shaft, and means operated by said movable support for operating said actuator to release said clutch from said pinion and thereby prevent operation of said mechanism when said movable support is moved from one position to another.

10. Gearing of the character described, comprising a stationary support, a drive shaft carried by said support, a pinion loosely mounted on said drive shaft, a clutch member on said drive shaft movable to and from position to lock said pinion to said drive shaft, automatic means for moving said clutch member to position to lock said pinion to said drive shaft, a movable support, mechanism carried by said movable support, gearing for operating said mecha-

nism from said pinion when said clutch member is in engagement with said pinion, and means operated by said movable support for disengaging said clutch member 5 from said pinion to prevent operation of said gearing and said mechanism when said movable support is moved from one position to another.

11. Gearing of the character described, 10 comprising a drive shaft, a pinion loosely mounted on said drive shaft, a movable support, mechanism to be operated carried by said movable support, gearing for operating said mechanism from said pinion, a clutch 15 member for locking said pinion to said drive shaft, a spring holding said clutch member in engagement with said pinion, a device for moving said clutch member out of engagement with said pinion in opposition to

said spring, and an actuator operated by 20 said movable support for moving said device when said movable support is moved from one position to another.

12. A gearing, comprising a stationary support, a drive shaft journaled in said support, a movable support, hinge members connecting said movable support with said drive shaft, a driven shaft mounted in said movable support, gearing for driving said driven shaft from said drive shaft, and means 25 operated by said movable support for rendering said gearing inoperative for driving said driven shaft from said drive shaft and thereby permit said driven shaft to stop, as an incident to movement of said movable support from one position to another, while said drive shaft continues in operation. 30 35

WILLIAM H. SARGENT.
